US0D1077834S

(12) **United States Design Patent** (10) Patent No.: **US D1,077,834 S**
Matsushima et al. (45) Date of Patent: ** Jun. 3, 2025

(54) **DISPLAY SCREEN OR PORTION THEREOF
WITH ICON**

(71) Applicant: **SONY GROUP CORPORATION**,
Tokyo (JP)

(72) Inventors: **Masanori Matsushima**, Tokyo (JP);
Miyuki Shirakawa, Tokyo (JP)

(73) Assignee: **SONY GROUP CORPORATION**,
Tokyo (JP)

(**) Term: **15 Years**

(21) Appl. No.: **29/881,174**

(22) Filed: **Dec. 28, 2022**

(30) **Foreign Application Priority Data**

Jun. 28, 2022 (JP) ..... 2022-013795 D

(51) **LOC (15) Cl.** **14-04**

(52) **U.S. Cl.**

USPC **D14/489**

(58) **Field of Classification Search**

USPC D14/489-495, 485-488

CPC G06F 3/048-04897; H04M 1/724-72484;

G06T 13/80; G06T 15/02

See application file for complete search history.

(57) **CLAIM**

The ornamental design for a display screen or portion thereof with icon as shown and described.

DESCRIPTION

The patent or application file contains at least one drawing executed in color. Copies of this patent or patent application publication with color drawing(s) will be provided by the Office upon request and payment of the necessary fee.

FIGURE is a front view of a display screen or portion thereof with icon showing our new design.

The dot-dash broken lines constituting a portion of a display panel or screen defining the boundaries of the claimed design form no part of the claimed design.

**1 Claim, 1 Drawing Sheet
(1 of 1 Drawing Sheet(s) Filed in Color)**
